Des. 234,002
Patented Dec. 24, 1974

234,002

FLOODLIGHT

Fred M. Gore, Dallas, and Glen H. McReynolds, Jr.,
Houston, Tex., assignors to Esquire, Inc., New York,
N.Y.

Filed Apr. 11, 1973, Ser. No. 350,152

Term of patent 14 years

Int. Cl. D26—03

U.S. Cl. D48—20 K

FIGS. 1, 2 and 3 are front, side and top views, respectively, of a floodlight embodying our design.

The flat surface on the front of the floodlight is a window.

We claim:

The ornamental design for a floodlight, substantially as shown and described.
